UNITED STATES PATENT OFFICE

JOHN EDWARD SYKES, OF HAREHILLS, LEEDS, ENGLAND

EXHAUST SILENCER

Application filed July 7, 1930, Serial No. 466,235, and in Great Britain April 16, 1929.

This invention relates to exhaust silencers for internal combustion engines, the chief object being to provide a new or improved exhaust silencer whereby the use of the ordinary expansion chamber on petrol driven motor vehicles will be obviated.

According to the invention, the exhaust silencer comprises a pipe embodying a series of baffle plates and adapted to be connected 10 at one end to the exhaust manifold of the engine, the other end of said pipe leading into an enlarged oyster-shaped receptacle or chamber having a restricted outlet and adapted to allow of a sudden expansion of 15 the gases on leaving the pipe and prior to passing out by way of said restricted outlet. The inlet end of the pipe may be connected to the exhaust manifold of the engine either directly or through the medium of a flexible 20 or other metal tube, and the baffle plates are preferably arranged in staggered formation from opposite sides of the pipe and inclined relatively to the axis thereof with their inner or leading edges directed toward the outlet 25 end so as to cause the exhaust gases to take a sinuous or zig-zag course through said pipe to the oyster-shaped receptacle or outlet chamber, while the outlet from the latter is preferably in the form of a narrow slit afforded 30 at the rear edge of the flattened and widest portion of said oyster-shaped receptacle or outlet chamber. The employment of the oyster-shaped outlet chamber or receptacle in conjunction with the baffled pipe obviates 35 back pressure and ensures efficient silencing.

In order that the invention may be clearly understood and readily carried into effect, the same will now be more fully described with reference to and by the aid of the accompanying drawings; wherein:—

Figures 1, 2 and 3 are respectively a side elevation and a plan view in which the pipe is partly broken away for the sake of clearness, and an end elevation of an exhaust 45 silencer constructed according to the invention.

Referring to the drawings, the exhaust silencer comprises a pipe 1, embodying a series of baffle plates 2 and adapted to be 50 connected at one end to the exhaust manifold

of the engine, the other end of said pipe 1 leading into an oyster shaped receptacle or outlet chamber 3. Said receptacle 3 is made separate from the pipe 1 and is formed with a neck 4 into which the pipe 1 is inserted. 55 The pipe 1 may be a tight fit in the neck 4 or the latter may be slit so as to give when the pipe is forced in and so that it can then be tightened by means of a collar 5 and nut and bolt 6, and in this connection the nut 60 and bolt 6 may also pass through a bracket (not shown) so as to support the silencer on the vehicle chassis. The pipe 1 is provided with a number of inclined baffles 2 arranged in staggered formation from opposite 65 sides and with their inner or leading edges directed toward the outlet end so as to cause the exhaust gases to take a sinuous course through said pipe 1. The baffles 2 are preferably separately formed and passed through 70 slits in the pipes so that they can be welded or otherwise suitably secured thereto. The rear edge of the oyster shaped receptacle or outlet chamber 3 is flattened and prevented from being forced outwardly by strengthening 75 bars 7 and holding bolts 8 passed therethrough. Thus the shape of the receptacle or outlet chamber 3 is such as to allow of a sudden expansion of the gases, whilst affording a restricted outlet.

I am aware it has before been proposed in exhaust silencers embodying a box or pipe leading directly into a restricted or "fish-tail" outlet to provide baffles in the box or pipe, said baffles being in the form of plates 85 arranged in staggered formation from opposite sides and inclined toward the outlet.

I claim:—

An exhaust silencer comprising a pipe adapted to be connected at one end to the 90 exhaust manifold of an engine, an enlarged substantially oyster-shaped receptacle connected to the opposite end of the pipe, said pipe having a series of staggered baffle plates disposed alternately on opposite sides thereof and inclined relative to the axis of the pipe, said baffles having their inner or leading edges directed toward the outlet so as to cause the exhaust gases to take a sinuous course through the pipe, said receptacle hav- 95 100

ing a restricted outlet to allow of a sudden expansion of the gases on leaving the pipe and prior to passing out by way of said restricted outlet, said outlet being in substantial alignment with the pipe to provide a through passage for the exhaust gases, the outer edge of said outlet being substantially flat to form a narrow slit for the escape of the exhaust gases, and means connected to said outer edge for preventing outward movement thereof.

JOHN EDWARD SYKES.
